RIDGE-FORMING MECHANISM THROW-OUTS FOR BLIND-STITCH SEWING MACHINES

Frank Parry, Trumbull, Conn., assignor to The Singer Manufacturing Company, Elizabeth, N. J., a corporation of New Jersey

Application June 7, 1952, Serial No. 292,262

9 Claims. (Cl. 112—176)

This invention relates to blind-stitch sewing machines and it has for its main object to provide an improved automatic means for varying the field of action of the ridge-forming element to effect the production of skip-stitches and anchor-strokes.

Another object of the present invention is to provide a simplified manually actuated throw-out for the ridge-forming element regulating means, whereby the machine can be conveniently changed from a skip-stitch machine to a continuous anchor-stitch machine.

Another object of the invention is to provide a manually actuated throw-out device for the skip-stitch mechanism of a blind stitch machine, which device when located in one of its two positions of adjustment will render the skip-stitch mechanism effective to produce successive anchor strokes and skip strokes and when in its other position of adjustment will render the skip-stitch mechanism effective to lock the work-table of the machine in its normal elevated work-presenting position.

Still another object of the invention is to provide a ridge-forming element elevation-regulating means which is effective to permit a micrometer adjustment of the normal working position of the ridge-forming element.

The foregoing and other objects and advantages, together with means whereby the same may be carried into effect, will best be understood from the following description of a preferred embodiment thereof illustrated in the accompanying drawings, in which:

Fig. 1 is a top plan view of a machine constructed in accordance with my invention, the bed cover-plate being removed and certain of the parts being in section better to illustrate the details of the machine.

Fig. 2 represents a vertical sectional view taken longitudinally of the base and through the standard and the work-table, illustrating the mechanism for periodically tilting the work-table in order to form skip stitches and anchor stitches.

Fig. 3 represents an enlarged horizontal sectional view taken substantially along the line 3—3 of Fig. 2, showing the skip-stitch anchor-link and the manner in which the same is supported for adjustment into and out of skip-stitch position.

Fig. 4 represents an enlarged vertical sectional view through the free end of the machine-base, showing the linkage connecting the work-table elevating spring to the work-table.

Fig. 5 represents an enlarged vertical sectional view taken transversely of the work-table adjacent the stitching point to illustrate the relation of the ridge-forming element to the presser-plate and the stitch-forming devices.

Fig. 6 represents a vertical sectional view taken substantially along the line 6—6, Fig. 1, illustrating the mounting for the skip-stitch eccentric together with the belt drive therefor.

Fig. 7 is an enlarged front elevation of the skip-stitch throw-out lever, showing, in full lines, the position of the lever when the skip-stitch mechanism is in operating

2

position, and, in dotted lines, the position of the lever when the skip-stitch mechanism is inoperative position.

Fig. 8 represents an enlarged horizontal sectional view taken substantially along the line 8—8, Fig. 2, showing the adjustable eccentric stop by which the normal working elevation of the work-table is controlled.

Fig. 9 is a schematic view of the skip-stitch mechanism with the anchor link in a position such that the skip-stitch mechanism imparts a periodic tilting motion to the work-table, thereby to form skip stitches and anchor stitches.

Fig. 10 is a view similar to Fig. 9, but with the anchor link shifted to a position in which no tilting motion is imparted to the work-table and consequently only anchor stitches are produced.

Referring to the accompanying drawings, the improved sewing machine includes a frame comprising a base or base-arm 10 having a hollow standard 11 rising from the rear right hand corner thereof. Extending laterally towards the left from the upper end of the standard is a horizontal upper arm 12, and extending forwardly from the left hand end thereof is a frame-arm 13. Attached to the free end of the arm is a stationary presser-plate or foot 14 against which the work is clamped by a pair of conventional vertically yieldable work-clamping members 15 carried by a work-table 16 which is supported by the base-arm 10.

Journalized in the horizontal upper arm 12 is a main rotary shaft 17 which, through the usual connections disclosed for example in the U. S. patent of Dearborn, No. 705,325, July 22, 1902, oscillates a needle shaft 18 which is journalized in the forwardly extending arm 13. Carried by the forward end of the needle shaft 18 is a curved needle 19 which oscillates directly above the presser-plate 14 and in a path transverse to the longitudinal axis thereof, the forward or work penetrating stroke being from left to right. Coöperating with the needle in the formation of chain-strokes is a looper 20 actuated in the manner shown in the U. S. patent of Dearborn, No. 639,669, December 19, 1899, from the main shaft 17. The work is fed rearwardly past the needle 19 by means of a four-motion feed-dog 21 which operates through a hole in the presser-plate 14 and in opposition to the vertically yieldable work-clamping members 15, all in the manner substantially like that disclosed in the U. S. patent of Dearborn, No. 1,592,446, July 13, 1926.

The work to be stitched is supported on the work-table 16 which is formed at its free left hand end as a tube or horn beneath the stitching and feeding mechanisms 50 and at its right hand end is enlarged into substantially rectangular form having a convex upper surface 22 (Fig. 2), and a pair of depending end-walls 23 and 24 (Fig. 1). The end walls 23 and 24 are preferably bored to receive the opposite ends of a horizontally disposed pivot-rod or shaft 25 journalized in upstanding lugs 30 and 31 which are integral with a bracket 32 detachably secured by screws 33 to the base 10.

The work-table 16 provides supporting means for the usual ridge-former 34 (Fig. 5) which functions in co-operation with the presser-plate 14 to form a bight in the material facilitating the penetration of the material by the curved needle 19 so as to form blind stitches. It will be understood that the material is bent or ridged as it is fed over the ridge-former 34 and in order to minimize the friction imposed on the material by the ridge-former during this bending action, the ridge-former is oscillated in the line of feed in a manner such that its forward movement is timed to coincide with the work-advance movement of the feed-dog 21. As will be seen in Figs. 1, 2 and 5, the ridge-former 34 is preferably clamped upon the outer end of a ridge-former carrying shaft 35 journalized in the work-table 16 and having se-

cured to its inner end a rock-arm 36. The rock-arm 36 is connected by a link 37 to the upper end of an upstanding rock-lever 38 secured on the exposed end of a pivot-shaft 39 journaled in one of the side walls of the base 10. Preferably clamped to the inner end of the pivot-shaft 39 is a downwardly extending rock-lever 40 connected by a pitman 41 to an eccentric 42 mounted on the main-shaft 17. Rotation of the main-shaft 17 will impart to the ridge-former 34 oscillations about the axis of the ridge-former carrying shaft in timed relation with the stitch-forming and work-feeding mechanisms.

As previously described, the work-table 16 is supported on the pivot-shaft 25 and is spring-biased, by means later to be described, into an elevated working position. This working position in the present machine is obtained by means of a novel manually controlled work-table height adjusting device located in the work-table and controlled by a thumb disk located at the right hand end of the work-table. The work-table height adjusting device is best shown in Figs. 1 and 2 and comprises a rotatable eccentric or cam-shaped stop 43 mounted on the lower end of a vertically disposed shaft 44 journaled adjacent its lower end in a bushing 45 pressed into a lug 46 integral with the work-table 16 and at its upper end in a bearing 47 provided in the work-table 16. The shaft 44 carries a worm-wheel 48 adjacent its upper end, and a spacing sleeve 49 maintains the shaft 44 in its proper elevated position in its bearings. Meshing with the worm-wheel 48 is a worm 50 carried on a hand operated shaft 51 which is journaled in the work-table and carries at its free end a thumb disk 52; the shaft 51 being constrained against endwise movement by the reduced end of a set screw 53 which enters an annular groove 54 in the shaft 51. Cooperating with the eccentric or cam stop 43 is an abutment element or plunger 55 which is adapted to be constrained against endwise movement, in which case the machine produces successive anchor stitches, or be reciprocated endwise for a limited extent, in which case the work-table is periodically raised and lowered and the machine produces skip stitches and anchor stitches. Assuming that the machine is adjusted so that the plunger 55 is constrained against endwise movement, then it will be understood that manual turning of the thumb-disk 52 will effect a turning of the eccentric stop 43 and, depending on the direction of movement of the eccentric stop, the work-table will be elevated or lowered relative to the free end of the frame-arm 13. It will be apparent that because of the large ratio between the worm 50 and worm-wheel 48 and the small rise or eccentricity on the eccentric stop 43, a very accurate adjustment of the position of the work-table can be obtained. This is especially advantageous when blind-stitching very thin fabrics.

As mentioned above, means are provided for either constraining the abutment plunger 55 against endwise movement or reciprocating the same in timed relation with the stitch-forming mechanism to produce successive anchor stitches and skip stitches. This skip-stitch means comprises a single mechanism equipped with a throw-out which can be operated whether or not the machine is running. As will be seen in Fig. 2, the plunger 55 is mounted to reciprocate in the end wall of the base 10, and at its inner end the plunger is fitted with a wrist-pin 56 mounted to turn in the spaced limbs of a yoke 56' formed on the forward end of a pitman-connector 57 whose other end is forked, as at 58, to embrace a slide-block 59 freely journaled on a skip-stitch rotary actuator or eccentric 60. The skip-stitch eccentric 60 (Fig. 6) is preferably formed integral with a belt-sprocket 61 which is freely journaled on a pivot-spindle 62 supported in bearings bushings 63 provided in the side-walls of the standard 11; the pivot-spindle 62 being constrained against endwise movement in its supporting bushings 63 by the stop-screws 64 threaded into the bushings. The slide-block 59 and the forked end of the pitman con-

nector 57 are maintained in cooperative relation on the eccentric 60 by a flanged collar 65 which is secured on the pivot-spindle 62. The belt-sprocket 61 is driven preferably by a clip-belt 66 from a smaller belt-sprocket 67 fast on the main-shaft 17; the ratio between the belt-sprockets 61 and 67 being of the order 2-to-1 so that when the skip-stitch mechanism is in operative position alternate anchor stitches and skip stitches are produced. Obviously, the ratio between the belt-sprockets can be of the order of 3-to-1 or 4-to-1, in which case a plurality of skip stitches are made between the anchor stitches. Also, it will be appreciated that gearing may be used, instead of belting, to drive the skip-stitch eccentric from the main-shaft 17.

Spring means is provided for maintaining the work-table 16 in its elevated working position determined by the selected position of adjustment of the eccentric stop 43. As shown in Figs. 1, 2 and 4, the pitman-connector 57 is formed with an offset rear end 68 into which is threaded a spring-tension-regulating screw 69 carrying a spring-connector 70 having a cross-bar 71 to which is hooked one end of a work-table elevating coil-spring 72. At its other end, the coil-spring 72 is secured to the inner end of a slide-rod 73 (Fig. 4) supported in the end-wall 25 of the base 10 and connected at its outer end by a short link 73' to one side face of a pivotally mounted rock-member 74. Connected to the other side face of the rock-member 74 is a link 75 connected to the depending front limb of the work-table 16. The linkage, including the slide-rod 73, rock-member 74 and link 75, provides means such that when the work-table is lowered by manual actuation of the usual knee-shift, the effort required by the operator becomes less as the work-table approaches its lowered position. This particular feature is fully described and claimed in another of my U. S. patent applications Serial No. 292,264, filed herewith and reference may be had to that application for a more complete description of the same. From the above description, it will be appreciated that the work-table elevation controlling eccentric stop 43 is yieldingly held in contact with the abutment plunger 55 by the coil-spring 72 which acts between the pitman-connector 68 and the work-table 16. It will be further understood that since the coil-spring 72 does act between the pitman-connector 68 and the work-table 16, and not between the base 10 and the work-table 16 as is customary in prior blind-stitch machines, the pressure developed by the coil-spring 72 is not transmitted to the skip-stitch eccentric 60, which additional pressure would increase the friction between the slide-block 59 and the fork 58 and increase wear, but is absorbed within the skip-stitch mechanism. The manner in which the coil-spring is mounted to eliminate the pressure exerted by the spring from being transmitted back to the skip-stitch driving mechanism eccentric 60 forms the subject of another one of my U. S. patent applications Serial No. 292,261, now Patent No. 2,681,629, dated June 22, 1954, filed herewith and reference may be had to that application for a more complete disclosure of this feature.

In order to render the skip-stitch mechanism effective or ineffective to tilt the work-table 16 about its pivotal support 25, a manually actuated linkage is provided which controls the movement of the pitman connector 57 such that it imparts a slight endwise reciprocation to the abutment plunger 55 or holds the same stationary. The control linkage is arranged between the pitman connector 57 and the base 10 and comprises an anchor-link 76 (Fig. 3) secured at its upper end to an adjusting shaft 77 journaled through the machine-base 10 and confined against endwise displacement relative to the base 10 by the hub of the anchor-link 76 and a collar 78 mounted on the adjusting shaft. Pivottally connected to the other end of the anchor-link 76, by a fulcrum-stud 79, is one end of a control-link 80 formed at its other end with a lateral bearing projection 81 on which is journaled

the pitman-connector 57; the bearing projection 81 and control link 80 being formed with a clearance bore 82 through which extends the adjusting shaft 77. The adjusting shaft 77 has secured on it, exteriorly of the base 10, a hand-lever 83 which is provided with a spring-biased ball-detent 84 cooperating with two detent depressions 85 formed in a plate 86 attached to the side wall of the base 10; the two depressions 85 defining an upper and a lower position of the fulcrum-stud connection 79 between the anchor-link 76 and the control-link 80. In the lower position of the fulcrum-stud 79, see Fig. 10, the control-link 80 is arranged so that its longitudinal axis is disposed substantially parallel with a line between the wrist-pin 56 and the axis of the skip-stitch pivot-spindle 62, in which lower position the control-link 80 swings an equal distance on opposite sides of the line between the wrist-pin 56 and the axis of the pivot-spindle 62 and does not force the pitman connector 57 to move endwise and impart any reciprocation to the abutment plunger 55. In fact, in the lower position of the fulcrum-stud 56, the abutment plunger 55 remains substantially stationary and thereby provides, in effect, a stationary stop which determines an elevated position of the work-table 16, in which elevated position consecutive anchor-stitches are formed.

When the hand-lever 83 is shifted to the full line position as shown in Fig. 7, the fulcrum-stud 79 is moved to its upper position as is shown in Fig. 9. When so shifted, the control link 80 assumes an inclined position with respect to the line between the wrist-pin 56 and the axis of the skip-stitch pivot-spindle 62. In this inclined position, the control-link 80 interferes with the free angular movement of the pitman connector 57 about the wrist-pin 56 and induces, in addition, a slight reciprocatory motion to the pitman connector 57 which is transmitted to the abutment-plunger 55, resulting in a periodic lowering of the work-table 16 so that alternate anchor and skip-stitches are formed.

From the foregoing, it will be understood that I have provided a throw-out for the ridge-forming mechanism of a blind-stitch sewing machine, which throw-out can be actuated at will for converting the machine from a skip-stitch machine to a continuous-anchor-stitch machine. Also, it will be appreciated that the throw-out is designed so that, in moving the hand lever 83 from alternate anchor and skip-stitch position to continuous-anchor-stitch position, it is unnecessary to manually adjust any stops or the like; the throw-out mechanism automatically locking the abutment-plunger 55 in a stationary position determining the normal elevated working position of the work-table and consequently the ridge-former 34.

Having thus set forth the nature of the invention, what I claim herein is:

1. In a blind-stitch sewing machine, the combination with a main frame including an overhanging arm, of a stationary presser-plate attached to the free end of said arm and provided with an opening, stitch-forming mechanism mounted on said arm and including a needle disposed for movement across said opening, a work-table mounted on said main frame and having a portion underlying the free end of said overhanging arm, a ridge-forming element located below said presser-plate for projecting a ridge of fabric upwardly through said opening into needle penetrating position, skip-stitch connections for at intervals moving said ridge-forming element relative to said overhanging arm to form anchor stitches and skip stitches, and a control linkage for constraining the motion of said skip-stitch connections, means for maintaining said control linkage in operative relation continuously with said skip-stitch connections, and manually operable means carried by said control linkage for shifting said linkage into a first position of adjustment in which said skip-stitch connections are effective to move said ridge-forming element toward and away from said overhanging arm and a second position of adjustment in

which said skip-stitch connections are rendered effective to maintain said ridge-forming element in a normally elevated position relative to said overhanging arm.

2. In a blind-stitch sewing machine, the combination with a main frame including an overhanging arm, of a stationary presser-plate attached to the free end of said arm and provided with an opening, stitch-forming mechanism mounted on said arm and including a needle disposed for movement across said opening, a work-table having a portion underlying the free end of said overhanging arm and mounted on said main frame for movement toward and away from said overhanging arm, a ridge-forming element supported by said work-table and located below said presser-plate for projecting a ridge of fabric upwardly through said opening into needle-penetrating position, skip-stitch connections for at intervals moving said work-table relative to said overhanging arm to form anchor stitches and skip stitches, a control linkage for constraining the motion of said skip-stitch connections, means for maintaining said control linkage in operative relation continuously with said skip-stitch connections, and manually operable means carried by said control linkage for shifting said linkage into a first position of adjustment in which said skip-stitch connections effect a movement of said work-table toward and away from said overhanging arm and a second position of adjustment in which said skip-stitch connections are rendered effective to maintain said worktable in a fixed position relative to said overhanging arm.
3. In a blind-stitch sewing machine, the combination with a main frame including an overhanging arm, of a stationary presser-plate attached to the free end of said arm and provided with an opening, stitch-forming mechanism mounted on said arm and including a needle disposed for movement across said opening, a work-table having a portion underlying the free end of said overhanging arm and mounted on said main frame for movement toward and away from said overhanging arm, a ridge-forming element supported by said work-table and located below said presser-plate for projecting a ridge of fabric upwardly through said opening into needle-penetrating position, skip-stitch connections including a movable abutment element for at intervals moving said work-table relative to said overhanging arm to form anchor stitches and skip stitches, and a control linkage associated with said skip-stitch connections and having a first position of adjustment in which movement is imparted through said abutment element to move said work-table toward and away from said overhanging arm and a second position of adjustment in which said abutment element is held stationary and acts as a stop to maintain said work-table in a fixed normally elevated position relative to said overhanging arm.
4. In a blind stitch sewing machine, the combination with a main frame including an overhanging arm, of a stationary presser-plate attached to the free end of said arm and provided with an opening, stitch-forming mechanism mounted on said arm and including a needle disposed for movement across said opening, a work-table having a portion underlying the free end of said overhanging arm and mounted on said main frame for movement toward and away from said overhanging arm, a ridge-forming element supported by said work-table and located below said presser-plate for projecting a ridge of fabric upwardly through said opening into needle-penetrating position, skip-stitch connections for at intervals moving said work-table relative to said overhanging arm to form anchor stitches and skip stitches, said skip-stitch connections including a rotary actuator, a movable abutment element supported by said main frame, and a pitman-connector connected at one end to said abutment element and at its other end to said rotary actuator, and a control linkage operatively connected to said pitman-connector and having one position of adjustment in which said pitman-connector is constrained to move said

abutment element and a second position of adjustment in which said pitman-connector is caused to turn about its connection with said abutment member without imparting any movement to said abutment member.

5. In a blind-stitch sewing machine, the combination with a main frame including an overhanging arm, of a stationary presser-plate attached to the free end of said arm and provided with an opening, stitch-forming mechanism mounted on said arm and including a needle disposed for movement across said opening, a work-table 5 mounted on said main frame and having a portion underlying the free end of said overhanging arm, a ridge-forming element located below said presser-plate for projecting a ridge of fabric upwardly through said opening into needle penetrating position, skip-stitch connections for 15 at intervals moving said ridge-forming element relative to said overhanging arm to form anchor stitches and skip stitches, said skip-stitch connections including a rotary actuator, a reciprocatory abutment element journaled in said main frame, and a pitman-connector pivotally connected at one end to said abutment element and actuated at its other end by said rotary actuator, and a throw-out control linkage operatively connected to said pitman-connector, said control linkage including a control-link 20 pivotally connected to said pitman-connector, an anchor-link pivotally connected to said control-link, and means for swinging said anchor-link into and out of a position in which the point of connection of the control-link with the anchor-link lies substantially in a straight line connecting the axis of rotation of the rotary actuator with the point of pivotal connection of the pitman-connector with the abutment element.

6. In a blind-stitch sewing machine, the combination with a main frame including an overhanging arm, of a stationary presser-plate attached to the free end of said arm and provided with an opening, stitch-forming mechanism mounted on said arm and including a needle disposed for movement across said opening, a work-table 35 mounted on said main frame and having a portion underlying the free end of said overhanging arm, a ridge-forming element located below said presser-plate for projecting a ridge of fabric upwardly through said opening into needle penetrating position, skip-stitch connections for at intervals moving said ridge-forming element relative to said overhanging arm to form anchor-stitches and skip 40 stitches, said skip-stitch connections including a rotary eccentric, a reciprocatory abutment element journaled in said main frame, and a pitman-connector pivotally connected at one end to said abutment element and actuated at its other end by said rotary eccentric, and a manually actuated throw-out control linkage operatively connected to said pitman-connector, said control linkage including a control-link having a bearing projection on which said pitman-connector is journaled, said bearing projection being bored to provide a clearance hole, an anchor-link 45 pivotally connected to said control-link, an anchor-link adjusting shaft journaled in said main frame and extending through the clearance hole in the bearing projection of said control-link, and means secured on said anchor-link adjusting shaft for retaining said anchor-link in a selected one of two positions.

7. In a blind-stitch sewing machine, the combination with a machine frame, a presser-plate upon said frame, a stitch-forming mechanism disposed above said presser-plate and including a thread carrying needle, and a work- 50

table movably mounted upon said frame in operative relation with said presser-plate, of an adjustable stop means carried by said work-table and operable to determine the normal operating position of said work-table relative to said presser-plate, said adjustable stop means including a stop-cam disposed to engage said machine frame, a shaft journaled in said work-table and carrying said stop-cam, a manually turnable member mounted on said work-table, and a worm and worm-wheel connection between said manually turnable member and said shaft.

8. In a blind-stitch sewing machine, the combination with a machine frame, a presser-plate upon said frame, a stitch forming mechanism disposed above said presser-plate and including a thread carrying needle, and a work-table movably mounted upon said frame in operative relation with said presser-plate, of an adjustable stop means carried by said work-table and operable to determine the normal operating position of said work-table relative to said presser-plate, said adjustable stop means including a stop-cam disposed to engage said machine frame, a first shaft journaled in said work-table and carrying said stop-cam, a second shaft also journaled in said work-table and arranged transversely of said first shaft, gearing interconnecting said first and second shafts, and a thumb-disk secured on said second shaft and disposed for convenient manipulation by the operator.

9. In a blind-stitch sewing machine, the combination with a main frame including an overhanging arm, of a stationary presser-plate attached to the free end of said arm and provided with an opening, stitch-forming mechanism mounted on said arm and including a needle disposed for movement across said opening, a work-table 30 mounted on said main frame and having a portion underlying the free end of said overhanging arm, a ridge-forming element located below said presser-plate for projecting a ridge of fabric upwardly through said opening into needle penetrating position, skip-stitch connections for at intervals moving said ridge-forming element relative to said overhanging arm to form anchor-stitches and skip 35 stitches, said skip-stitch connections including an oscillatory member, a pivot pin joining said oscillatory member to said skip-stitch connections, and a control linkage associated with said skip-stitch connections to define a pivotal axis with respect to said main frame for movement of said oscillatory member, said control linkage having a first position of adjustment in which said pivotal axis with respect to said main frame is defined remote from the axis of said pivot pin joining said oscillatory member to said skip-stitch connections whereby said skip 40 stitches are effective to move said ridge-forming element toward and away from said overhanging arm, and a second position of adjustment in which the pivotal axis with respect to said main frame is defined substantially coincident with the axis of said pivot pin joining said oscillatory member to said skip-stitch connections whereby said skip-stitch connections are rendered effective to maintain said ridge-forming element in a normally elevated position relative to said overhanging arm.
